UNITED STATES PATENT OFFICE.

HARRY TARSHIS, LOUIS BERZON, AND JOSEPH BREZIN, OF PHILADELPHIA, PENNSYLVANIA, ASSIGNORS OF ONE-FOURTH TO LOUIS ARON, OF PHILADELPHIA, PENNSYLVANIA.

BAG FASTENING AND LOCKING MECHANISM.

1,245,132.

Specification of Letters Patent.

Patented Oct. 30, 1917.

Application filed May 8, 1917. Serial No. 167,304.

To all whom it may concern:

Be it known that HARRY TARSHIS, LOUIS BERZON, and JOSEPH BREZIN, citizens of the United States, residing at 1837 N. 31st street, 5 1426 S. 20th St., and 2625 Douglas St., respectively, Philadelphia, in the county of Philadelphia and State of Pennsylvania, have invented new and useful Improvements 10 in Bag Fastening and Locking Mechanism, 10 of which the following is a specification.

This invention relates to fastening and locking mechanism of the type employed for effecting the retention of the jaws of a traveling bag in closed and locked positions, 15 and has for its primary object to provide a conveniently operated mechanism of this character for simultaneously effecting the operation of the several latch elements thereof, so that the bag may be more expeditiously and readily opened.

Another object is to produce bag fastening mechanism possessing substantial and practical features of construction, and having novel locking means coöperating there- 25 with for preventing the actuation of the latch elements by unauthorized persons.

With these and other objects in view, as will appear as the description proceeds, the invention consists in the novel features of 30 construction, combination of elements and arrangement of parts to be hereinafter fully described and pointed out with particularity in the appended claims.

In the drawings—

Figure 1 is a perspective view of the hinged jaw frames of a satchel or like receptacle, illustrating the application of the present invention thereto.

Fig. 2 is a vertical sectional view taken 40 through the fastening mechanism, comprising one of the preferred embodiments of the invention.

Fig. 3 is a bottom plan view thereof, showing the mechanism detached from the 45 satchel frames.

Fig. 4 is an enlarged vertical sectional view disclosing more particularly the locking means.

Fig. 5 is a transverse sectional view, taken 50 through the midlength of Fig. 2,

Fig. 6 is a detail perspective view of one of the latch elements.

Fig. 7 is a similar view of one of the plungers.

Fig. 8 is a detail view of one of the sliding locking plates.

Fig. 9 is a view of one of the manually operated slides.

Fig. 10 is a perspective view of a slightly modified form of the invention, illustrating 60 the same applied to hinged satchel frames.

Fig. 11 is a vertical longitudinal sectional view thereof.

Fig. 12 is a top plan view.

Fig. 13 is a transverse sectional view 65 taken along the line 13—13 of Fig. 11.

Fig. 14 is a perspective view of one of the latch elements.

Fig. 15 is a similar view of the lock lever.

Fig. 16 is a similar view of the plunger 70 of the modified form of the invention.

Similar characters of reference denote corresponding parts throughout the several views of the drawings.

Referring to the drawings and more particularly to the form of the invention shown in Figs. 1 to 9 inclusive, the invention is disclosed as being employed in conjunction with the usual hinged jaw frames 1 and 2 of a traveling bag or satchel, which frames 80 are of the ordinary angular construction, and are adapted to have the body 3 of the satchel secured thereto in any suitable manner. Sliding latch arms 4 and 5 are carried by the frame 1 for interlocking coöperation 85 with substantially hook-shaped catches 6, rigidly secured to the frame 2, whereby when the arms and elements are in active engagement, the frames will be connected so as to close the entrance to the satchel. The 90 latch arms 4 are positioned adjacent to the central portions of the frame 1 and protrude inwardly, while the latch arms 5 are disposed near the ends of the frame, this arrangement being common in bag construction. However, in the ordinary form of traveling bag now in general use, it is necessary to operate the arms 4 and 5 separately to permit of the opening of the 95 jaws. This process is rather laborious and 100

complicated and, therefore, it is the aim of the present invention to provide mechanism for operating the latch arms in a simultaneous and convenient manner, and to obviate unnecessary operations incident to the opening of a bag.

To this end the arms 5 are provided with integral, or otherwise formed, horizontally and inwardly extending bars 7, which are adapted to extend parallel with the frame 1, and to be located exteriorly or above the latter. The inner contiguous extremities of the bars are formed with openings 8, through which the latch arms 4 are adapted to pass, whereby upon the movement of the arms 4 the coöperating latch arms 5 will be synchronously operated, as will be clearly understood. A channeled casing 9 is adapted to cover and protect the bars 7, said casing being secured in a rigid manner upon the frame 1 by providing the same with projecting lugs 10, which pass through openings 11 provided in the frame, and are bent over so as to prevent the removal of the casing from its secured position upon the frame. A plate 12 is positioned within the casing and is interposed between the bars 7 and the upper surface of the frame 1, said plate being employed in the capacity of a wear plate. Alining slots 13 are formed in the frame 1 and in the plate 12, and are utilized to receive the arms 4 and 5 so as to permit of a controlled sliding movement of the latter. Other slots 14 are provided in the bars 7, and in which are positioned helical springs 15, the latter having their outer extremities bearing upon the end walls of the slots 14, while the opposite extremities are adapted to engage with angularly bent pins 16 carried by the casing 9, thus enabling the latch arms to be normally retained in positions to interlock with the catches 6 of the frame 2.

In order to permit of the convenient manipulation of the latch arms, the casing 9 has secured to and positioned above the central portion thereof, a housing 17. Slidable over the upper surface of said casing and partly positioned within the housing are oppositely movable slides 18, the latter having rigidly secured thereto the upper extremities of the arms 4, whereby the movement of the slides will result in the synchronous movement of all the latch arms. Knobs 19 are carried by the outer extremities of the slides to permit of the convenient manipulation of the latter, that is, by simply gripping the knobs with the fingers of one hand, and moving them toward each other, the end and central latch arms will be given simultaneous movement, to permit of the opening or separation of the frames 1 and 2. When the knobs are released, the spring 15 will automatically return the latch arms to fastening or locking positions.

65 Locking means are provided in conjunc-

tion with the latch arms, to prevent the latter from being surreptitiously actuated to effect the opening of the bag. The means preferably consists of a plunger 20 having a head 21, which is vertically movable within a boss 22, integrally formed with the housing 17. A cap 23 is secured to the collar 21, and protrudes above the boss, so that the plunger 20 as a whole may be manually depressed. A shank 24 depends from the head 21 and extends through guide openings provided in the casing 9 and the frame 1. A helical spring 25 is adapted to surround the shank and is interposed between the head 21 and the upper surface of the casing 9, said spring serving to retain the plunger 20 in a normally elevated position. A bar 26 is also carried by the head 21 and extends parallel to the shank 24, and through guide openings provided in the frame and casing, 85 said bar being formed with an opening 27, the purpose of which will presently appear.

Slidably supported upon the lower surface of the casing 9 is a locking plate or bolt 28, having an inwardly extending tongue 29 formed therewith, said tongue being adapted to frictionally engage with one side of the bar 26, and is maintained in such engagement by means of a coil spring 30, which abuts against a fixed element 31, carried by the casing, and surrounds and engages with a protruding finger 32 formed with the plate 28. Thus it will be seen that when the plunger 20 is depressed or lowered, against the normal tendency of the spring 25, the opening 27 provided therein will be brought into registration with the tongue 29, so that the latter will be thrust into the opening 27 by the action of the coil spring 30, which forces the plate forwardly, and will thereby lock the plunger 20 against further vertical movement. This operation results in positioning the head between the inwardly moving slides 18, thereby effectively preventing the actuation of the latter with the view of operating the latch arms. In order to remove the tongue 29 of the plate from engagement with the opening of the bar 26, so as to allow the plunger 20 to return to an unlocking position, said plate or bolt 28 is provided with upwardly bent key-engaging projections 33, which are movable within slots provided in the upper wall of the casing 9, the upper extremities of said projections lying within the housing 17. A key-receiving opening 34 is formed in the walls of said housing in substantial registration with the projections 33, so that a key (not shown) when inserted within said slots will lie contiguous to the projections. Thus it will be seen that by rotating said key the latter will be forced into engagement with the projections and will force the bolt rearwardly against the tension of the spring 30, so that the tongue 29 will be drawn out of 125

the opening 27. This permits the plunger 20 to return to its unlocking position within the boss 22, by the action of the spring 25, which is allowed to expand when the bolt 28 is removed from engagement with the bar 28.

From the foregoing description it is thought that the following remarks with reference to the operation of the invention will be clearly understood. Upon the closing of the frames 1 and 2 the hook catches 6 of the frame 2 will engage with the spring-pressed latch arms 5 so as to fasten the bag in a closed condition. Then in order to lock the bag in the latter position the plunger 20 is depressed, so that the head 21 thereof will lie between the slides 18, thus preventing the latter from being moved inwardly. In order to open the bag, a key is inserted into the opening 34 and is revolved so as to force the bolt 28 out of engagement with the plunger, thereby permitting the latter to return to its normal position. When so situated, the slides 18 may be moved inwardly against the influence of the springs 15, thus effecting the simultaneous operation of the latch arms 4 and 5, so that the latter will be drawn out of engagement with the hook elements 6, thus permitting the frames 1 and 2 to be readily separated.

In Figs. 10 to 16 inclusive of the drawings there has been shown a slightly modified form of the invention. In this form use is made of the usual swinging jaw frames 40 and 41 of a traveling bag or the like, the frame 40 carrying sliding latch arms 42 and 43, which are adapted to engage with rigid catches 44 carried by the frame 41. The upper extremities of the arms 43 extend through slots formed in the frame 40 and into a channeled casing 45 rigidly mounted upon the exterior or upper surface of said frame. Alining rods or their equivalents 46 are connected to the upper extremities of the latch arms 43 and extend in parallel relation to the frame 40, and lie within the casing 45. The inner ends of the rods 46 are connected in any suitable manner to the latch arms 42, whereby when the latter are operated so as to clear their coöperating catches 44, similar movement will be imparted to the outer arms 43. To effect the actuation or manipulation of the latch arms 42, the upper extremities of the latter are provided with finger-engaging knobs or slides 47, which lie partially within a housing 48 and extend exteriorly of the latter so as to be conveniently grasped. Coil springs 49 surround the outer extremities of the rods 46 and abut against reduced portions of the casing 45, and against the upper extremities of the latch arms 43, the normal tendency of said springs being to force the latch arms in a fastening or locking position with respect to the catches 44.

In order to retain the arms 42 and 43 in

locking engagement with the catches 44, there is provided a vertically movable plunger 50, which is adapted to be interposed between the arms 42. Recesses 51 are provided in the head 53 of the plunger 50, and are normally located in alinement with projecting pins 52 carried by the inner faces of the arms 42, whereby the latter may be freely moved to effect the movement of the latch arms, when the plunger 50 is in its normal or elevated position. However, by depressing the plunger 50 the recesses 51 thereof will be brought out of registration with the pins 52, so that the enlarged head will be positioned immediately between said pins to prevent movement on part of the arms 42. The plunger 50 is retained in a lowered position by providing the same with an opening or notch 53' adapted to be engaged by a locking lever 54, pivotally mounted as at 55 upon the depending portion 56 of a plate 57 carried by the frame 40, and secured to the latter beneath the casing 45. The lever 54 is provided with a bifurcated extremity 57' which is adapted to surround the lower extremity of a rod 58 depending from and constituting the shank of the plunger 50, a spring 59 being situated between the enlarged head 53, and the extremity 57' of the locking lever. It will thus be seen that when the plunger 50 is depressed, the opening or notch 53' thereof will be lowered so as to aline with the hook-shaped end or tongue 60 of the lever 54, so that the same will serve as a bolt which is thrust into the notch 53' by the action of the spring 59, thus locking the plunger 50 against further movement, and likewise the sliding arms 42. The plunger 50 may be restored to its normal unlocking position by providing the housing 48 with a key-receiving slot 61, the latter being located adjacent to the upper extremity of the lever 54. It will thus be seen that by inserting a key into the slot 61 and by rotating the same, the hook-shaped extremity or tongue 60 of the lever 54 will be drawn out of the notch 53', thus permitting the plunger 50 to return to its normal position by the action of the spring 59, thus permitting the arms 42 and 43 to be freely operated. A thumb button or cap 62 is formed on the upper end of the plunger 50 so as to permit of the manual operation of the latter, and a casing 63 is adapted to surround the locking mechanism of the lower extremities of the arms 42, so that clothing carried by the bag will not interfere with their operations.

From the foregoing it will be seen that there is provided mechanism whereby the objects of the present invention have been achieved, and all of the advantageous features above mentioned are, among others, present. The mechanism described is extremely simple, yet efficient in construction,

reliable in operation, and not likely to become out of order.

It will be understood, however, that we do not limit ourselves to the particular form 5 of the invention shown; and that various slight changes can be made without departing from the spirit of the invention, the scope of which being defined in the appended claims.

Having described the invention what is 10 claimed as new and patentable is:

1. In a bag fastener, the combination with the jaw-latching mechanism, alined horizontal slides connected therewith, and a 15 spring holding the slides normally spread; of a plunger movable vertically in the space between the slides and having a head of a size to fill it and a reduced shank depending therefrom, a guide for the shank, a spring 20 surrounding the shank and normally raising the head out of said space, and a lock en-

gaging the plunger when depressed, as and for the purpose set forth.

2. In a bag fastener, the combination 25 with the jaw-latching mechanism, alined horizontal slides connected therewith, and yielding means holding them normally spread; of a plunger movable vertically in the space between the slides and having a head of a size to fill it and a reduced shank 30 depending therefrom, the latter having an opening, a spring-pressed locking element having a tongue to normally engage said opening when the plunger is depressed, key-actuated means for retracting said element, 35 and a spring normally raising the plunger as and for the purpose set forth.

In testimony whereof we affix our signatures.

HARRY TARSHIS.
LOUIS BERZON.
JOSEPH BREZIN.
